ASSEMBLING DIE

Abraham Drucker, Joseph Gluckman, and Isidore Guralnik, New York, N. Y.; said Gluckman and said Guralnik assignors to said Drucker

Application April 3, 1934, Serial No. 718,770

7 Claims. (Cl. 79—5)

This invention relates to improvements in button assembling dies, and has for its primary object to provide an improved die structure for assembling the parts of covered buttons where-
5 by quantity production may be expedited.

Button assembling dies for covered buttons having two metal shells, comprise upper and lower die members and an intermediate re-
versible die member. It has been the practice to
10 provide a latch on the outside of the upper die member for the purpose of locking the said mem-
ber in position when receiving the upper shell and covering material of the button; the said latch being adapted to release the upper die mem-
ber when the final operation of assembling the
15 two shells of the button was to be performed.
This outer latch had a tendency to bind and it was necessary to constantly hammer against
the latch to pry it apart from the central spindle
20 into free operating condition. The jamming and hammering caused damage to the mech-
anism and injury to the fingers of the operator.

An object of this invention is to provide im-
proved locking means to take the place of the
25 said latch, the said locking means being posi-
tioned internally of the upper die member and comprising a radially movable ball adapted to
engage a peripheral groove in the center spindle and a vertically slid-
30 able spring-pressed pin hav-
ing an upper circular notch adapted for engage-
ment with said ball when the ball is seated in
the peripheral groove; a lower circular notch in
the said pin being provided for receiving the
35 ball when it is out of contact with the peripheral
groove, the said locking mechanism serving the
same purpose as the above mentioned latch but
in a much more efficient manner.

Another object of this invention is to provide
auxiliary locking means to prevent accidental
40 disengagement of the working parts of the upper
die member.

With the above and other objects in view, the
invention will be hereinafter more particularly
45 described, and the combination and arrangement
of parts will be shown in the accompanying draw-
ings and pointed out in the claims which form
part of this specification.

Reference will now be had to the drawings,
50 wherein like numerals of reference designate
corresponding parts throughout the several views,
in which:

Figure 1 is a vertical sectional view illustrating
the initial step, with the upper shell and cover-
55 ing material pushed into the upper half of the
die and the upper half of the button shaped to
its final form.

Figure 2 is a vertical sectional view illustrating
the second step, with the lower shell and cover-
60 ing material pushed into an intermediate re-

versible die member and the lower half of the
button shaped to its final form.

Figure 3 is a vertical sectional view illustrating
the method of assembling the two halves of the
button with each other.

Fig. 4 is an exterior view of the dies in the as-
sembling position, shown in Fig. 3. Fig. 5 is a
vertical sectional view of a set of combination dies
and a modified form of locking means. Fig. 6 is
a plan view of a center plunger.

In the illustrated embodiment of the invention,
the numeral 10 indicates a suitable base having
an aperture 11, adapted to receive the lower end
of a vertically disposed flanged spindle 12. The
flanged spindle 12 may be fixed in position by a
screw 13. The lower die member 14 is slidably
75 mounted for vertical movement on the spindle 12.
The spindle is provided with a longitudinal key-
way 15 adapted to receive the end of a screw 16
threaded into the reduced lower portion 17 of the
lower die member 14.

A coil spring 18 serves to raise the die member
14, and the screw 16 serves to limit the upward
movement of the die member 14 under the action
of the spring. The upper end of the die member
14 is provided with a central recess 19, an annular
85 portion 20, and a seating face 21.

The upper die member 22 is slidably mounted
for vertical movement on a spindle 23 having a
concave lower end 24 adapted to contact with the
convex upper end 25 of the spindle 12. The up-
90 per portion 26 of the spindle 23 may be designed
to be fastened by means of a screw 27 to a recip-
rocable member 28 of a press (not shown) and be
operated by hand or by a foot treadle.

The spindle 23 is provided with a peripheral
groove or reduced portion 29 having a beveled up-
per portion 30 and a curved lower portion 31 ter-
minating in a sharp corner 32. A ball 33 inserted
22 is designed to engage the said peripheral
groove. A pin 35 is slidably mounted in an aper-
ture 36 in the upper die member 22 and is pro-
vided with an upper circular notch 37 designed
for engagement with the ball when the ball is
seated in the peripheral groove 29. The slid-
able pin 35 is also provided with a circular
notch 38 positioned below the notch 37. The
notch 38 is designed to receive the ball 33 when
it is out of contact with the peripheral groove 29.
A coil spring 39 is positioned in the aperture 36
and contacts with the upper surface of the slid-
able pin 35 and serves to keep the ball in forced
engagement with the peripheral groove 29. The
105 slide pin 35 projects out from the aperture 36
below the face 40 of the upper die member 22.

As shown in Figure 1, the slide pin 35 is free
to enter the annular portion 20 without coming in
contact with the lower face 41 of the said annular
portion. The upper die member 22 depends from

the spindle 23 in locked relation therewith and permits the upper shell 42 and the covering material 43 of the button to be pushed into the upper die member 22.

5 As shown in Figure 1, a detent 99 has been placed in the aperture 34 of the upper die member 22 and is pressed laterally against the spindle 23 by a spring 100. The detent 99 is designed to engage and interlock with the lower portion of the 10 groove 29 when the upper die member 22 is in its lower position on said spindle. It is to be noted that the detent or locking means 99 is carried by the upper die member 22 and that the spindle 23 furnishes engaging means for interlocking with 15 the said detent.

As shown in Figure 2, a reversible die member 44 is provided to operate in conjunction with and intermediate of the upper and lower die members. The reversible die member 44 is provided with an 20 axial bore 45 terminating at one end in a beveled or flared portion 46, an annular portion 47, a seating face 48, and an exterior flange 49. A rod 50 of smaller diameter than the axial bore 45 is slidably mounted in the reversible die member 44. A 25 keyway 51 is provided in the rod 50 and a screw 52 threaded in the die member 44 and in engagement with said keyway serves to limit the sliding movement of the rod in each direction. The rod 50 is provided with a concave face 53 at one end 30 designed to receive the lower shell 42 of the assembled button 54 shown in Figure 3. The other end of the rod 50 is provided with a collar 55 and a concave face 56. The collar 55 serves as an abutment in the reversible die member 44 in the 35 assembling position shown in Figure 3.

The two shells of the button with the covering materials are assembled in three operations in the following manner by means of the above described dies. As shown in Figure 1, the lower shell 40 42 of the button 54 is placed upon the convex upper end 25 of the spindle 12 and the covering material 43 for the lower shell is placed on the lower face 41 of the lower die member 14. The upper die member 22 is then lowered together with the lower die member 14 against the action 45 of the spring 18 until the lower shell 42 and covering material 43 are forced upwardly into the bore 57 of the upper die member 22.

As shown in Figure 2, the upper shell 58 of the 50 button 54 is placed upon the convex upper end 25 of the spindle 12 and the covering material 59 for the upper shell is placed on the lower face 41 of the lower die member 14. The reversible die member 44 and the upper die member 22 are then lowered together with the lower die member 55 14 against the action of the spring 18 until the upper shell 58 and covering material 59 are forced upwardly into the bore 45 of the reversible die member 44.

60 The reversible die member 44 is then reversed as shown in Figure 3 and the upper die member 22 lowered until the projecting beveled annular portion 47 of the member 44 strikes the vertically movable locking member 35, forcing it up and releasing the radially movable locking member 33. The locking members are thus automatically released and permit the upper die member 22 to move from its locked position shown in Figures 1 and 2 into contact with the flange 60 of the movable spindle 23, as shown in Figure 3, when the 65 two halves of the button 54 are assembled with each other.

Figure 4 shows an exterior view of the dies in the assembling position assumed in Figure 3. The 75 absence of any external latch members is readily

noticeable. It will be noted that the locking members 33 and 35 are entirely housed and concealed in the upper die member 22, and there is no chance for jamming the mechanism and injuring the fingers of the operator.

80 Figure 5 shows a set of combination dies 61 adapted for assembling buttons or buckles, etc., having a central aperture. The set of dies 61 are provided with a modified embodiment of our improved locking means. The set of dies 61 comprises a lower die member 62 slidably mounted on a fixed spindle 63, a reversible die member 64, and an upper die member 65 slidably mounted on a movable spindle 66. The spindle 66 is provided with a radial cylindrical aperture 67. The upper die member 65 is provided with a radial cylindrical aperture 68 of the same diameter as the aperture 67. A cylindrical pin 69 has been inserted in the aperture 68 and a spring 70 positioned in the aperture 68 contacts with the pin 69 and serves to keep said pin resiliently pressed in a radial direction. The pin 69 is provided with an aperture 71 for the passage therethrough of a pin 72. The pin 72 is slidably mounted in an aperture 73 in the upper die member 65 and a compression spring 74 positioned in the upper portion of the aperture 73 contacts with the upper surface of the slideable pin 72 so as to keep the pin resiliently pressed in a longitudinal direction. The pin 72 is provided with reduced portions 75 forming a head 76 designed for engagement with the upper surface of the pin 69. The lower ends of the reduced portions 75 are provided with downwardly beveled portions 77.

90 In the position shown in Figure 5, the pin 72 110 has been pushed up against the spring 74 by coming in contact with the flat surface 78 of the die member 64. The beveled portion 77 in its upward movement actuated the cylindrical pin 69 to the left and out of locking position from the aperture 115 67. The movable spindle 66 is thus free to move down till the flange 79 comes into contact with the upper die member 65. A pin 80 has been provided in the upper die member 65 and in sliding engagement in a slot 81 in the spindle 66 and serves to 100 prevent accidental disengagement of the upper die member 65 from its spindle 66.

105 Combination assembling dies must be constructed with the upper and lower die members in longitudinal alignment and non-rotatable with the 110 respective spindles. We accordingly prefer to make the said spindles of rectangular cross-section corresponding to the outer perimeter of the shells being assembled so as to prevent rotation of the die members on their respective spindles. The 115 dies must be adapted to assemble shells covered with material of different thickness or weight. If the bore 82 in the reversible die member 64 is made large enough to admit a thick covering material, when a light covering material is used, the weight 120 of the center plunger 83 causes the inserted shell and covering material to fall out from said member. We have accordingly found it necessary to provide frictional means for preventing the shell and covering material from being displaced from 125 operating position in the reversible die member.

130 As shown in Figure 6, the center plunger 83 is provided with a friction plate 84, having a long slot 85 which terminates in an aperture 86. The slot 85 and aperture 86 extend through the thickness of the plate 84. It is thus possible to spread apart the side walls 87, 88, defining the slot and to cause a frictional pressure to be exerted against the inner circumferential surface defining the bore 82 in the reversible die member 64. It is also pos- 135 140 145 150

sible to repeatedly spread apart the side walls defining the slot as the wear progresses.

An aperture 89 has been provided in the lower die member 62 for receiving the downwardly projecting portion of the slideable pin 72 in the first operation corresponding to Figure 1, and a through aperture 90 has been provided in the friction plate 84 for receiving the downwardly projecting portion of said pin in the second operation, corresponding to Figure 2.

A pin 91 projecting from the upper die member 65 and pins 92, 93, projecting from the reversible die member 64, are designed for engagement with an opening 94 in the lower die member 62 and serve to align the die members 62, 64 and 65 in non-rotatable relation.

A screw 95 in the die member 62 and in engagement in a slot 96 in the fixed spindle 63 limits the axial movements of the lower die member 62 on its spindle 63. A screw 97 in the reversible die member 64 and in engagement with a slot 98 in the center plunger 83 serves to retain the center plunger in the reversible die member 64.

While we have shown and described two embodiments of our invention which have given good service in practice, it is possible to make other modifications within the scope of the appended claims. It is possible to utilize our improvements for button assembling dies used for assembling buttons that are covered with cloth on both sides or only on one side or which are not covered, and for other purposes such as for assembling buckles, etc.

Having thus described our invention, we claim:

1. In button assembling dies of the class described, comprising upper and lower die members and a reversible intermediate member, a vertically movable spindle upon which said upper die member is slidably mounted, means limiting the axial movement of the upper die member on its spindle, means for locking the upper die member on its spindle when said upper and lower die members are brought together for projecting the upper shell of the button into the upper die member, said locking means comprising a vertically slideable spring-pressed pin having an upper circular notch for engagement with a ball mounted in a peripheral groove in the spindle of the upper die member, said pin having a lower circular notch extending further radially outwardly than the upper notch for receiving said ball when out of contact with said peripheral groove and means for preventing accidental disengagement of said locking means from said upper die member.

2. In assembling dies of the class described, comprising upper, lower and intermediate die members, a vertically movable spindle upon which an upper die member is slidably mounted for movement into upper and lower operating positions, means for locking said upper die member on its spindle in said lower position, said locking means comprising a vertically slideable and spring pressed pin having a reduced cross-sectional portion, and a radially movable locking member, said radially movable member being adapted for locking engagement with said reduced portion in said vertically slideable pin, and means for preventing accidental disengagement of said die members.

3. In assembling dies of the class described, comprising upper, lower and intermediate die members, a vertically movable spindle upon which an upper die member is slidably mounted for

movement into upper and lower operating positions, means for locking said upper die member on its spindle in said lower position, said locking means comprising a longitudinally slideable member and a laterally movable locking member, said laterally movable member being adapted for locking engagement with said longitudinally slideable member, and means for preventing disengagement of said die members.

4. In assembling dies of the class described, a vertically movable spindle upon which an upper die member is slidably mounted for movement into upper and lower operating positions, means for locking said upper die member on its spindle in said lower position, said locking means comprising a longitudinally slideable locking member and a laterally movable locking member, said laterally movable locking member being adapted for locking engagement with said longitudinally slideable locking member, said locking members being housed inside said upper die member.

5. In assembling dies of the class described, a spindle upon which an upper die member is rotatably and slidably mounted for movement into upper and lower operating positions, means for locking said upper die member on its spindle in said lower position, said locking means comprising a longitudinally slideable locking member and a laterally movable locking member, said laterally movable locking member being adapted for locking engagement with said longitudinally slideable locking member for locking said upper die member on said spindle in any rotatable position thereon, said locking members being housed inside said upper die member.

6. In assembling dies of the class described, upper and lower die members, a fixed spindle upon which the lower die member is mounted for vertical movement, spring means yieldingly sustaining the lower die member, a vertically movable spindle upon which the upper die member is slidably mounted for movement into upper and lower operating positions, means limiting the axial movements of said die members relative to the respective spindles, locking means in said upper die member for preventing movement of said member on its spindle in said lower position, a reversible die member positioned between the upper and lower die members in different operating positions, said reversible die member having a longitudinal bore for reciprocating movement therein of a center plunger, and frictional means for retaining said center plunger in operating position in said reversible die member.

7. In assembling dies of the class described, comprising upper, lower and intermediate die members, a vertically movable spindle upon which said upper die member is slidably mounted for movement into upper and lower operating positions, means for locking said upper die member on its spindle in said lower position, said locking means comprising a movable spring pressed member and a reduced portion on said spindle and detent means movable relative to said upper die member for interlocking with said reduced portion when said upper die member is in said lower position, said intermediate and said lower die members respectively having one of its faces formed to permit coaction with said upper die member when said locking means is in locked position.
